UNITED STATES PATENT OFFICE.

WALTER R. SCHLAGE, OF SAN FRANCISCO, CALIFORNIA, ASSIGNOR TO SCHLAGE LOCK COMPANY, OF SAN FRANCISCO, CALIFORNIA, A CORPORATION OF CALIFORNIA.

DOOR LATCH.

Application filed March 6, 1926. Serial No. 92,703.

This invention relates to door latches and especially to improvements over the structure shown in Patent Number 1,489,675, issued to me April 8th, 1924.

5 The patent referred to shows a form of door latch which is actuated by an inner and an outer door knob and a push button carried by the inner knob which actuates a mechanism whereby the door knob is locked 10 against rotation.

The present application also shows a form of door latch which is actuated by an inner and an outer knob. A push button is carried by the inner knob, but it serves another function, that is, it does not lock the outer knob against rotation, but, conversely 15 releases the knob so that it may be freely rotated without actuating the latch mechanism.

20 To fully describe the general latch structure and particularly the mechanism whereby the outer knob is released, reference will be made to the accompanying drawings in which

25 Fig. 1 is a horizontal section of the latch showing its position in the door.

Fig. 2 is a similar view showing the latch mechanism partly broken away and partly in section, the push button being in this instance depressed to release the outer knob.

30 Fig. 3 is a sectional view taken at right angles to Figs. 1 and 2, the knob spindles being broken away.

Fig. 4 is a cross-section taken on line 4—4 35 Fig. 1.

Fig. 5 is a cross-section taken on line 5—5 Fig. 1, but showing the retractor in retracted position.

Fig. 6 is a perspective view of the inner 40 knob spindle.

Fig. 7 is a perspective view of the retractor.

Fig. 8 is a perspective view of the retractor guide.

45 Fig. 9 is a perspective view of the telescoping section of the outer knob spindle.

Fig. 10 is a perspective view of the push button and the pusher bar carried thereby.

The general latch structure shown in the 50 drawings in this application is fully disclosed and described in my copending application entitled "Door lock", filed May 8th, 1923, Serial Number 656,335, but a brief de-

scription of the latch structure is nevertheless thought necessary in order that the push 55 button and the releasing mechanism actuated thereby, which forms the subject matter of this application, may be fully understood.

It might be stated that the latch structure here illustrated consists of a bolt unit 60 generally indicated at A and a bolt actuating unit generally indicated at B, see Figs. 1, 4 and 5. The unit B is contained in a cup-shaped housing generally indicated at 2, and the unit A is contained in a cylindrical-shaped elongated housing generally indicated at 3. The unit A contains a bolt 4 to which is attached a retractor bar or plate 5, see Figs. 4 and 5. The end of this plate is provided with lugs 6 and these are engaged by a pair of fingers 7 which form a part of a retractor generally shown in Fig. 7. The retractor is held within the cup-shaped housing 2 and is actuated therein by a retractor guide, the general structure of 65 which is shown in Fig. 8. In other words, the housing 2 contains a retractor guide such as shown in Fig. 8 and a retractor such as shown in Fig. 7 and means are employed for imparting a reciprocal movement to the 70 retractor so that the fingers 7 carried thereby may impart a reciprocal movement to the retractor plate 5 and the bolt 4 carried thereby.

The reciprocal movement is imparted to the retractor by means of a pair of spindle members which are substantially identical in construction, one of the spindles being shown in perspective in Fig. 6. This particular spindle will hereinafter be referred to as the inner spindle. The two spindles 85 are otherwise clearly shown in Fig. 1 and the spindles are indicated by the numerals 8 and 9. The spindles are cylindrically shaped as shown in Figs. 1 and 6 and their inner ends are provided with retractor lugs 90 generally indicated at 10 and 11. The inner spindle carries a knob indicated at 12 and the outer spindle a knob which is indicated at 13. Both spindles project into the cup-shaped housing 2 of the unit B and they are 95 so positioned that the retracting lugs 10 and 11 will engage a horizontal plate 14 formed on the retractor. The spindle 8 is journaled at its inner end in the cup-shaped housing and is journaled at its outer end in an 100 extension 15 of an escutcheon plate 16. The 105

outer spindle is similarly journalled at its inner end in the housing 2 and at its outer end in an extension 17 forming part of an escutcheon plate 18. The knobs are keyed or otherwise secured to their respective spindles and as such impart a rotating movement to the spindles when the knobs are grasped and turned. The spindles are separated with relation to each other so that either knob may be grasped and rotated independently of the other. Rotation of either spindle through means of their knobs causes the retracting lugs 10 or 11 to engage the plate 14 on the retractor and as such forces it inwardly within the retractor guide shown in Fig. 8 against the tension of the spring 19.

The fingers 7 on the outer end of the retractor are in engagement with the lugs 6 of the retractor plate 5 and the bolt 4 is thus retracted by rotation of either spindle, the door being opened by rotating either knob so as to retract the retractor and the bolt, and the door is closed by merely releasing either knob as they are returned to a normal latching position by means of a spring 19 and a second spring 20 mounted in the housing 3 and engaging the inner end of the bolt 4. These springs are placed under tension when the retractor and bolt are retracted and this tension is depended upon to restore the parts to normal position. In other words, the door is automatically latched by projection of the bolt 4 through means of the springs 19 and 20.

35 The main object of the present invention is to provide a mechanism whereby the outer knob and spindle may be rendered inoperative. This is accomplished as follows: The outer spindle 9, as previously stated, is substantially identical in construction to the inner spindle 8. That is, it is cylindrical in cross-section and elongated. Mounted within the inner end of the spindle 9 is a cylindrical telescoping section 21, see Figs. 1, 2, 3 and 9. The inner end of this telescoping section is closed by an end plate 22 and it carries the retractor lug 11. A key or lug member 23 is secured on the telescoping cylindrical section 21 and this key projects into a slot 24 formed on the inner end of the spindle 9, the key forming a connection between the member 21 and the spindle, which insures rotation of the two members in unison when turning movement is imparted to the knob 13.

Secured to the end plate 22 on the side opposite the retracting lug 11 is a yoke 25. Secured within the spindle 9 is a plate 26 and interposed between the plate 26 and the plate 22 is a spring 27. This spring is held in central position by an annular projection 28 on plate 26 and also by the yoke member 25. The function of the spring is that of maintaining the member 21 in projected position where the retracting lug 11

will engage the plate 14 on the retractor. The member 21 will hereinafter be referred to as the telescoping spindle section as it is telescoped within the spindle 9 a sufficient distance to bring the retracting lug 11 out of engagement with the plate 14 when it is desired to render the outer knob and spindle 9 inoperative. For instance by referring to Fig. 2 it will be noted that the spring 27 is compressed and that the telescoping spindle section is telescoped within the spindle 9 so that it assumes a position where lug 11 cannot engage the plate 14 on the retractor. In this position it is possible to freely rotate the knob 13 and the spindle 9 in either direction without retracting the retractor or the bolt 4 actuated thereby. In other words the latch is in this instance rendered inoperative not by locking the outer knob and spindle against rotation as described in my Patent Number 1,489,675 previously referred to, but by releasing the outer knob and spindle so that it may freely rotate without retracting the retractor and the bolt. This is accomplished as follows. The inner knob 12 is provided with a central opening 30 in which is mounted a push button 31. Attached to the push button is a pusher bar 32. This bar extends through the retractor and the retractor guide and it also extends through a central perforation formed in the plate 22 of the telescoping spindle section. The outermost end of the pusher bar engages the bottom of the yoke 25 when the button 31 is depressed as shown in Fig. 2. The telescoping spindle section is forced inwardly within the spindle 9 to assume the position shown in Fig. 2 and when the push button is released or projected it assumes the position shown in Fig. 1. When the push button is depressed and the telescoping spindle section is forced into the spindle 9, lug 11 is maintained out of engagement with the plate 14 on the retractor, but when the push button is released or projected the telescoping spindle section is automatically projected by the spring 27 and lug 11 is then in a position where it will engage the plate 14 on the retractor. It is, therefore, obvious that the door is locked by merely depressing the push button 31 as such depression moves lug 11 out of engagement with the plate 14 on the retractor thereby rendering the outer knob and spindle inoperative. Thus it may freely rotate in either one direction or another without releasing the bolt 4 and the door is therefore locked from the exterior, but projection of the push button and the telescoping spindle section renders the latch operative from the outside as rotation of the knob and spindle will, in that instance, cause engagement of the lug 11 with the plate 14 and thereby cause retraction of the bolt 4.

It is essential that means be provided for

retaining the push button, the retractor bar and the telescoping spindle section when in telescoped position as shown in Fig. 2. This is accomplished by providing a latch member 33 on the pusher bar. The forward face of the latch member is cam-shaped as shown; it partially enters a slot 34 formed in the retractor when the push button is in extended position. Inward movement of the pusher bar by depression of the button 31 causes the cam face of the latch 33 to engage the retractor and to force it inwardly against the tension of the spring 19. The latch thus passes in under the retractor and the retractor immediately moves back into place when the end of the latch 33 passes the retractor as shown in Fig. 2. The retractor thus engages the inner shoulder of the latch 33 and locks the pusher bar and push button when in a depressed position thereby retaining the telescoping spindle section in depressed or released position. The door remains locked from the exterior as long as the push button is depressed as anyone trying to enter from the outside can only rotate the knob and such rotation will in no manner affect the retracting mechanism or the bolt. A person on the inside, may, however, unlock the door by merely rotating the inner knob 12. Such rotation causes the retracting lug 10 to engage the plate 14 on the retractor and such engagement forces the retractor inwardly against the tension of the spring 19 and that portion of the retractor which engages the rear shoulder of the latch 33 is thus forced inwardly to release the latch. The pusher bar when released is automatically restored to the position shown in Fig. 1 where the push button is extended as the inner end of the pusher bar is engaged by the yoke carried by the telescoping spindle section. This in turn is projected to operating position by the spring 27 and it accordingly restores the pusher bar to normal released position. It is accordingly apparent that the door is locked by merely depressing the push button 31 and that it can only be released from the interior and by rotation of the inner knob. Rotation of the outer knob when the button is in depressed position is of no avail as the telescoping spindle section is depressed and as such can have no effect on the retracting mechanism.

While certain features of the telescoping spindle section and the mechanism actuating the same are more or less specifically illustrated I wish it understood that various changes may be resorted to within the scope of the appended claims, similarly, that the materials and finish of the several parts employed may be such as the experience and judgment of the manufacturer may dictate.

Having thus described my invention what

I claim and desire to secure by Letters Patent is—

1. In a latch of the character described, a housing, a bolt mounted therein, an inner and an outer knob journaled in the housing, means actuated by each knob whereby the bolt may be retracted and means carried by the inner knob whereby the outer knob and bolt actuating mechanism is released so as to be free to rotate without retracting the bolt. 75

2. In a latch of the character described, a housing, a bolt mounted therein, an inner and an outer knob journaled in the housing, means connected with the outer knob whereby the bolt is retracted, means connected with the inner knob whereby the bolt is retracted and means carried by the inner knob whereby the outer knob and the connected bolt retracting mechanism is released to prevent retraction of the bolt. 80

3. In a latch of the character described, a housing, a bolt mounted therein, an inner and an outer knob journaled in the housing, means actuated by either knob whereby the bolt may be retracted and means carried by the inner knob whereby the outer knob and connected bolt retracting mechanism is released to prevent retraction of the bolt. 90

4. In a latch of the character described, a housing, a bolt mounted therein, a retractor connected with the bolt, an inner and an outer spindle, a lug on each spindle engageable to actuate the retractor and connected bolt and means carried by the inner spindle whereby the lug on the outer spindle may be displaced to prevent engagement with the retractor. 95

5. In a latch of the character described, a housing, a bolt mounted therein, a retractor connected with the bolt, an inner and an outer spindle, a lug on the inner spindle engageable with the retractor, a telescoping spindle in the outer spindle, a lug on the telescoping spindle also engageable with the retractor, and means for longitudinally displacing the telescoping spindle and its lug to prevent engagement with the retractor. 105

6. In a bolt of the character described, a housing, a bolt mounted therein, a retractor connected with the bolt, an inner and an outer spindle, a lug on the inner spindle engageable with the retractor, a telescoping spindle in the outer spindle, a lug on the telescoping spindle also engageable with the retractor, and means carried by the inner knob for displacing the telescoping spindle and lug to prevent engagement of the lug with the retractor. 110

7. In a latch of the character described, a housing, a bolt mounted therein, an inner and an outer spindle, a knob on each spindle for imparting a rotating movement thereto, a bolt actuating member on each spindle, a

retractor connected with the bolt and engageable by the bolt actuating member on each spindle, and means whereby the bolt actuating member on the outer spindle may be displaced longitudinally to permit free rotation of the outer spindle without engagement of the bolt actuating member and the retractor.

8. In a latch of the character described, a housing, a bolt mounted therein, a retractor connected with the bolt, an inner and an outer spindle, a knob on each spindle for imparting a rotating movement thereto, a lug on the inner spindle engageable with the retractor, a lug mounted for telescoping movement on the outer spindle, a push button in the inner spindle and a pusher bar connected with the button and engageable with the telescoping lug to move it out of engagement with the retractor.

9. In a latch of the character described, a housing, a bolt mounted therein, a retractor connected with the bolt, an inner and an outer spindle, a knob on each spindle for imparting a rotating movement thereto, a lug on the inner spindle engageable with the retractor, a lug mounted for telescoping movement on the outer spindle, a push button in the inner spindle a pusher bar connected with the button and engageable with the telescoping lug to move it out of engagement with the retractor, and means for retaining the push button and the pusher bar when the lug and the outer spindle have been moved to a position out of engagement with the retractor.

10. In a latch of the character described, a housing, a bolt mounted therein, a retractor connected with the bolt, an inner and an outer spindle, a knob on each spindle for imparting a rotating movement thereto, a lug on the inner spindle engageable with the retractor, a lug mounted for telescoping movement on the outer spindle, a push button in the inner spindle, a pusher bar connected with the button and engageable with the telescoping lug to move it out of engagement with the retractor, means for retaining the push button and the pusher bar when the lug on the outer spindle has been moved to a position out of engagement with the retractor, and means actuated by rotation of the inner knob for releasing the push button and pusher bar to permit return of the lug and engagement thereof with the retractor.

11. In a door latch a spindle consisting of two sections each turnable independently of the other, a bolt, means on each spindle actuated by rotation of the spindles for retracting the bolt, and means on one spindle for moving the opposite spindle longitudinally so that it may be freely rotated without retracting the bolt.

12. In a door latch a spindle consisting of two sections each turnable independently of the other, a bolt, means on each spindle actuated by rotation of the spindles for retracting the bolt, and means on one spindle for moving the opposite spindle longitudinally so that it may be freely rotated without retracting the bolt, and means actuated by the other spindle for automatically restoring the second named spindle to operative position.

13. In a door latch a spindle consisting of two sections each turnable independently of the other, a bolt, means on each spindle actuated by rotation of the spindles for retracting the bolt, and means on one spindle for moving the opposite spindle longitudinally so that it may be freely rotated without retracting the bolt and means actuated by rotation of the other spindle for automatically restoring the longitudinally movable spindle to operative position.

14. In a latch mechanism of the character described, an inner and outer knob, a bolt adapted to be retracted thereby, means carried by the inner knob to release the outer knob so as to permit it to freely rotate without retracting the bolt, and means actuated by turning movement of the inner knob for automatically restoring the outer knob to operative position.

15. In a latch mechanism of the character described, a rotary spindle, a second spindle longitudinally movable and also capable of being rotated, a bolt, means on each spindle for retracting the bolt and means carried by the first named spindle for moving the second named spindle longitudinally to a position where it may freely rotate without actuating the bolt.

16. In a latch mechanism of the character described, a rotary spindle, a second spindle longitudinally movable and also capable of being rotated, a bolt, means on each spindle for retracting the bolt, means carried by the first named spindle for moving the second named spindle longitudinally to a position where it may freely rotate without actuating the bolt, and means actuated by rotation of the first named spindle for automatically restoring the second named spindle to operative position so that the bolt will be retracted upon rotation of the second named spindle.

17. In a latch mechanism of the character described, a tubular spindle, an inner knob mounted thereon, an outer knob, a bolt, means actuated by rotation of either knob for retracting the bolt, a push button centrally disposed in the inner knob, and means connected with the push button and extending through the tubular spindle and adapted upon depression of the button to release the outer knob so as to permit it to freely rotate without restricting the bolt.

18. In a latch mechanism of the character described, an inner and an outer knob, a bolt adapted to be retracted by rotation of either knob, a push button centrally disposed in the inner knob, said push button when depressed adapted to release the outer knob so as to permit it to freely rotate without re- tracting the bolt, and means actuated by a turning movement of the inner knob for automatically restoring the push button to normal position and the outer knob to an operative position.

WALTER R. SCHLAGE.
